(57) **CLAIM**

The ornamental design for a door strike extension plate, as shown and described.

DESCRIPTION

FIG. 1 is a perspective view of the instant invention;
FIG. 2 is a front view thereof;
FIG. 3 is a rear view thereof;
FIG. 4 is a left side view thereof;
FIG. 5 is a right side view thereof;
FIG. 6 is a top view thereof; and
FIG. 7 is a bottom view; and,
FIG. 8 is a perspective view of the instant invention “as installed.”

The broken lines are for illustrative purposes only and form no part of the claimed design.
